US0D1083018S

(12) **United States Design Patent** (10) **Patent No.:** **US D1,083,018 S**
(45) **Date of Patent:** **** Jul. 8, 2025**

(54) **ELECTRONIC INSECT KILLER**

(71) Applicant: **Shaowei Liang**, Shenzhen (CN)

(72) Inventor: **Shaowei Liang**, Shenzhen (CN)

(**) Term: **15 Years**

(21) Appl. No.: **29/915,135**

(22) Filed: **Oct. 26, 2023**

(30) **Foreign Application Priority Data**

Oct. 25, 2023 (EM) 015038328-0001

(51) **LOC (15) Cl.** **22-06**

(52) **U.S. Cl.**

USPC **D22/123**; D22/122

(58) **Field of Classification Search**

USPC D22/119-123; D30/199; D26/26, 41,

D26/24, 113, 119, 120, 366

CPC A01M 1/00; A01M 5/00; A01M 13/00;

A01M 17/00; A01M 27/00; A01M 23/00;

(57) **CLAIM**

The ornamental design for an electronic insect killer, as shown and described.

DESCRIPTION

FIG. 1 is a front, right and top perspective view of an electronic insect killer, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings illustrate portions of the electronic insect killer that form no part of the claimed design.

1 Claim, 8 Drawing Sheets
